TISSUE DISPENSER

Louis M. Zedric, Jr., Canton, Ill.

Application September 8, 1953, Serial No. 26,736

Term of patent 14 years

(Cl. D4—3)

FIG. 1.

FIG. 2.

FIG. 3.

FIG. 4.

FIG. 5.

FIG. 6.

Fig. 1 is a front elevation of a tissue dispenser embodying my new design;

Fig. 2 is a side elevation of the tissue dispenser embodying my design and may be considered as either or both of the sides of such design;

Fig. 3 is a rear view thereof;

Fig. 4 is a top elevation of the tissue dispenser;

Fig. 5 is a sectional view taken along the line 5—5 of Fig. 1 showing the contours of the outer surfaces of the tissue dispenser; and

Fig. 6 is a perspective view thereof shown in reduced scale.

The roller and paper disclosed in Figs. 3 and 5 by means of broken lines are disclosed only for the purpose of illustration.

I claim:

The ornamental design for a tissue dispenser, substantially as shown and described.
